REFRIGERATION APPARATUS

Delos P. Heath, Hillsdale, Mich.

Application July 10, 1937, Serial No. 152,891

5 Claims. (Cl. 62—108.5)

This invention relates in general to containers for liquid and in particular to trays for ice making or dessert freezing employed in domestic refrigerators.

5 It is an object to provide an ice cube freezing tray that will allow quick freezing of ice and easy removal of ice from the tray.

It is an object to provide a low cost tray of simple construction that can be operated by an 10 average householder.

It is an object to provide a more sanitary construction for a liquid freezing container that is readily cleaned.

15 It is an object to provide a tray that will automatically free itself from ice cubes during the freezing process.

It is an object to provide a low cost, simple and strong tray lifting device.

In the drawing:
20 Fig. 1 is a plan view of the tray with the tray lifting device shown dotted.

Fig. 2 is a perspective of the metallic sides and bottom members of the tray with lifter shown dotted.

25 Fig. 3 is a perspective view of the flexible tray ends fixed together by the flexible ice cube partitions.

Fig. 4 is a part plan view of a modification of Fig. 1 tray end.

30 Fig. 5 is a plan view in section along line I—I Figs. 2 and 3, showing a modification of the flexible means of Fig. 3 employed to seal the tray ends to the tray sides and bottom.

Like numerals refer to like parts.
35 Numeral 1, Fig. 1, indicates a metallic sheet possessing qualities of resisting corrosion and ability to transfer heat by conduction and to withstand temporary deformation without attaining a permanent set. I prefer using a thin 40 sheet of stainless steel or aluminum of spring like properties. This sheet may be formed in a press or brake to provide tray side wall portions, 5, tray flat bottom portion, 6, between the side walls, and if desired, tray rails 15 which are a 45 continuation of the side walls 5.

End walls 4, seal to 1 to form tray end walls. 50 Ends 4 and their connecting wall 2 and ice cube partitions 3, I may mold as shown in Figure 3 from a flexible, elastic, waterproof material that has the property of easily freeing itself from ice. I may employ gum rubber or an artificial rubber such as "Neoprene", for this purpose. The distance apart between the inside of ends 4, in the unassembled view, Fig. 3, is slightly less than the 55 distance between the opposite edges 11, of the

sheet metal bottom and side wall element of Fig. 2. The connecting wall 2 is capable of being stretched to allow ends 4 to be dropped over the edges 11. The ends 4 are somewhat more rigid than 2 but are flexible enough to adapt themselves to the edges of 11 and under the tension of 2, to seal watertight to 11 against the hydraulic pressure exerted by fluids placed in the tray 1.

An inwardly projecting collar or collars 13 at the tops or other portions of the ends 4, shoulder 10 against the top or other portions of side wall 5 and/or bottom 6 to assist in positioning ends 4 and also to reinforce 4 and distribute the pull of 2.

U-shaped lifting wire 10 has its ends loosely 15 looped through holes 7 at the rear end of 1, and its front mid portion 16 serves as a handle for the ice tray and as a lever working in the vertical plane to break the tray from the ice upon the tray shelf. Downward pressure upon 16 causes its cam 20 formed portions 9 to exert upward pressure upon rails 15 and downward pressure upon ice tray shelf 18 which is contacted by 9 while freezing ice. This action releases the rear end of the ice tray, and an upward pull of 16 breaks the front end 25 loose from 18.

In Fig. 4, modification, I have shown integral lips 12 projecting from 4 to assist in sealing 4 to edges 11. I may also employ these lips to seal along the inside of the sides 5 and bottom 6 as 30 shown by dotted lines.

It will be understood that the elastic member 2 exerting sealing pressure upon the ends 4, may also be constructed of a rigid material having an axial hole extending longitudinally through 2 35 and enclosing spring means attached to the end walls 19. Fig. 5 such a spring means is indicated by the dotted line in the wall 21. Also I may provide a spring means exterior to the side walls 5 to exert sealing tension upon the ends 19. This means is shown in Fig. 5 by elements 14 which may be metallic springs or elastic material such as rubber. The ends 19 in Fig. 5 are reinforced by inserted material 22 molded into the softer material forming the sealing portion of end 4. 40 The assembly of Fig. 5 allows ends 19 to be easily 45 removed and permits the use of metallic ice cube grids which will reduce the freezing time required with rubber grid.

To provide the ice cube tray Fig. 1 with automatic ice cube freezing means, I mold wall 2 with a bottom longitudinal section less than its top longitudinal section as shown in Fig. 1 and fabricate portions 3 in a similar manner. Metallic sheet 1 is cut and formed to bring the opposite 50

edges 11 at bottom 6 farther apart than the tops of the opposite edges 11 of sides 5. The bottoms of ends 4 when assembled with sheet 1 then project outwardly as shown by dotted lines 17, Fig. 1. 5 In operation, end 4 is placed over edges 11 at one end of sheet 1. The connecting wall 2 is then stretched and the other end 4 is released against the other end of sheet 1 with projection 13 resting upon the top of side walls 5. The watertight tray thus formed, is filled with water to a level of approximately one-eighth inch below the top of wall 2. Because bottom 6 and sides 5 are an integral metallic sheet and 6 is in direct heat conducting contact with the evaporator ice tray 10 shelf 18, ice cubes are more rapidly made than in trays with rubber bottoms. As the ice expands during freezing, pressure is exerted upon the side walls 5, bottom 6, ends 4, connecting walls 2, and ice cube partitions 3. Because 2 and 4 and 3 15 are tapered the longitudinal stresses set up by the ice forced the grid with its ends 4 upwardly. Water leaks do not occur as this upward movement of 2, 3 and 4 only takes place where the liquid has experienced a change of state. 20 25 To bring the bottom edges of the ends 4 clear of the tray shelf 18 it will be noted that in Fig. 5 are shown the depressions 20 which are flat to provide sufficient area to contact with 18 to rapidly conduct heat, and are of sufficient depth 30 to raise ends 4 above 18.

There are many manufacturing advantages in this construction. For example it will be noted that structure 1 of Fig. 2 may be rolled from strip stock and individual tray sections sawed off to 35 whatever length desired.

I claim:

1. In a refrigerating apparatus, an ice freezing tray comprising a flat metallic bottom, extending upwardly at opposite sides to form side walls, a 40 rubber ice cube forming element adapted to seal

against said bottom and side walls, said rubber element having end wall portions adapted to seal over the opposite ends of said metallic bottom and side walls to form removable end walls for said ice tray. 5

2. In a refrigerating apparatus, an ice freezing tray having a single metallic sheet for tray bottom and tray side walls, and rubber end walls adapted to seal against said sheet, said end walls being a single rubber molded element. 10

3. In a refrigerating apparatus, an ice tray bottom having side walls on opposite sides formed from a single metallic sheet, removable end walls adapted to seal against said metallic sheet in watertight relationship, spring means to exert 15 sealing pressure upon said end walls, said metallic sheet and said end walls adapted to freeze ice cubes in a domestic refrigerator.

4. In a refrigerating apparatus an ice freezing tray having a single metallic sheet for the tray 20 bottom and the tray side walls, removable end walls adapted to seal water tight against the front and rear edges of said bottom and side walls, and a U shaped wire member having its ends looped through holes in the upper and rear 25 portions of said sheet and extending exteriorly along the said side walls and around the front of said tray.

5. In a refrigerating apparatus, an ice cube freezing tray having a single metallic sheet for 30 tray bottom and tray side walls, removable end walls adapted to seal against the edges of said bottom and said side walls in water tight relationship to provide a container for the freezing of ice, tension means exterior to the space bounded by said container walls, said tension means adapted to provide the pressure required to seal said end walls to the edges of said bottom and said side walls. 35
